UNITED STATES PATENT OFFICE.

JAMES ALLAN MACDONALD, OF BOSTON, MASSACHUSETTS.

SINEW EXTRACTOR.

Application filed December 14, 1925. Serial No. 75,176.

This invention relates to a sinew extractor of the type shown by the Congdon Patent, No. 941,759, dated November 30, 1909, said extractor consisting of a base adapted to be attached in a vertical position to a fixed upright support, a forwardly extending foot-holder fixed to the base and having a forked end portion, a hand lever connected at its inner end with the base by a pivot located below and at one side of the foot-holder, the lever being movable in a vertical plane, and a leg-engaging member or claw including jaws extended laterally from the lever at a point intermediate the length of the lever on the side adjacent to the foot-holder, the jaws being adapted to engage an enlarged portion of a fowl's leg below the foot-holder when the lever is raised, and operating to separate the leg from the foot and extract the sinews when the lever is moved downward, all as more particularly set forth by the Congdon patent, which discloses a leg-engaging member whose jaws are rigidly attached to the lever.

The present invention is an improvement on the device of the Congdon patent, and is embodied in a leg-engaging member which is pivoted to the lever, instead of being rigidly attached thereto, so that said member turns on the lever when the latter is moved downward, and the jaws of the member exert a downward pull without such flexure of the leg as would be liable to break the latter.

Of the accompanying drawings, forming a part of this specification—

Figure 1 is a front elevation of a sinew extractor embodying my improvement, the lever being fully lowered.

Figure 2 is a side elevation of the same.

Figure 3 is a side elevation, showing the lever fully raised.

Figure 4 is a side elevation, showing the lever partly lowered.

Figure 5 is a front elevation, the parts being as shown by Figure 3.

Figure 6 is a perspective view, showing the leg-engaging member separately.

Figure 7 is a fragmentary view similar to a portion of Figure 3, showing the leg-engaging member arranged to engage a relatively small leg.

The same reference characters indicate the same parts in all of the figures.

a designates a base adapted to be secured to a wall by screws or otherwise. *b* designates a foot-holder which is an arm or

bracket projecting forward from the base and having a bifurcated end. The space between the fingers of the forked end is made wide enough to secure the bony part of the leg, as shown by Figures 3, 4 and 5, and the adjacent faces or edges of said fingers are beveled and provided with a sharp edge on the upper side of the lower finger over which the leg may be easily broken, as shown by the Congdon patent.

c' designates the hand lever connected by a pivot *c*, to ears on the base, the pivotal connection being arranged as heretofore, below and at one side of the foot-holder.

The leg-engaging member in the Congdon patent is a claw, arranged on and rigidly attached to the lever *c'* near its pivot, and projects laterally from that side of the lever adjacent the foot-holder, so that when the lever is fully raised on its pivot, the claw engages the leg below the foot-holder, and then, as the lever is moved downward, the fleshy part of the leg is drawn down, while the bony part remains fixed in the foot-holder, so that the sinews are extracted from the fleshy part of the leg, as described by the Congdon patent.

In carrying out my invention, I substitute for the claw fixed to the lever *c'*, a leg-engaging member composed of a neck 12, bearing on the side of the lever *c'* adjacent the foot-holder, a shank 13, projecting from one side of the neck through an orifice 14, in the lever, means such as a nut 16, engaged with a threaded portion of the shank for retaining the shank in the orifice, and leg-engaging jaws 17, projecting from the opposite side of the neck, and spaced apart by a leg-receiving throat 18 (Figure 6).

The shank 13 is preferably a headed bolt extending through an orifice in the neck, and through an orifice 14 in the lever, the head of the bolt bearing on one side of the neck, and the nut bearing on the opposite side of the lever. The jaws are therefore free to turn on the lever during the downward movement of the latter, so that they exert a downward pull on the fleshy portion of the leg, without flexing the bony portion, and therefore without liability of breaking the latter. This liability exists when a leg-engaging member or claw rigidly secured to the lever is employed, as in the device of the Congdon patent.

The lever *c'* may be provided with a plurality of orifices 14, located at different dis-

tances from the pivot c^2 . Either orifice is adapted to receive the shank 13, so that the leg-engaging member may be located at different distances from the lever pivot c^2 , thus 5 enabling the extractor to be adjusted according to the size of the leg.

The jaws 17 are preferably more widely spaced apart at one end of the jaws than the other, as best shown by Figure 6, so that 10 by inverting the jaws, they may be adapted to engage fleshy portions of the different sizes.

The throat 18 between the jaws is preferably of such width that it is adapted to receive relatively large legs, such as those of turkeys. To enable the jaws to engage relatively small legs, such as those of hens, etc., I may provide the jaws with slots 20, which are open at the outer ends of the jaws, the 20 slots having leg-engaging edges collectively forming jaws adapted to engage a relatively small leg, the jaws being turned, as shown by Figure 7.

I claim:

25 1. A sinew extractor comprising a base, a forwardly extended foot holder attached thereto having a forked end portion, and a hand lever connected at its inner end por-

tion to said base, by a pivot located below and at one side of the foot holder, the lever being movable on its pivot in a substantially vertical plane, and a leg-engaging member composed of a base bearing on the side of the lever adjacent the foot holder, a shank projecting from one side of the base 35 through an orifice in the lever, means retaining the shank in the orifice, and leg-engaging jaws projecting from the opposite side of the base and spaced apart by a leg-receiving throat, the foot holder and jaws 40 being engageable with a foot and leg when the lever is in a raised position, and operable by a downward movement of the lever to separate the leg from the foot and extract the sinews, the jaws turning on the lever during said downward movement, so that they exert a downward pull without flexing the leg.

2. A sinew extractor as specified by claim 1, the jaws being provided with slots open 50 at the outer ends of the jaws, and having leg-engaging edges collectively forming jaws adapted to engage a relatively small leg.

In testimony whereof I have affixed my signature.

JAMES ALLAN MACDONALD.
